and the following is claimed as my invention:

1. In a brassière body front portion, the combination of:

(a) a single piece of cloth, the top edge having secured thereto, by a double line of stitching, the cloth strip 2; the bottom edge having secured thereto, by similar lines of stitching, a plurality of spaced strips 3, preferably five in number, the cloth at one end being formed with a hem 4 to which eyelets 5 are sewed or otherwise secured, the opposite end being formed with a hem 6 having secured thereto the piece 6a carrying metal hooks 7 for cooperation with the eyelets 5 in conventional manner;

(b) a central portion 16 bounded by double hems 12, one fork of each strip 13, a bottom strip 3 and top strip 2; the portion 16 being formed centrally and inwardly from top strip 2 to bottom strip 3 with twin tucks 17, 17, as clearly shown in Fig. 3, tapering slightly from top to bottom, lines of stitching 18, 18, Fig. 6, defining a separation portion in the body front portion upon the outer face of the garment;

UNITED STATES PATENT OFFICE

2,607,039

BRASSIÈRE

Martha A. Richardson, Akron, Ohio

Application August 21, 1950, Serial No. 180,630

1 Claim.

(Cl. 2—42)

1. Brassière body front portion.

This invention relates to improvements in brassières. One object is to provide a brassière designed to be worn comfortably while supporting the busts in natural form, completely preventing bust droop. A further object is to provide a brassière that affords maximum bust support without the wearer really being conscious of the presence of the garment.

Another object is to provide a brassière having a loose fitting bottom portion that is very comfortable and entirely sufficient due to the fact that an inside center portion provides maximum support, tension on the shoulders from the straps being wholly absent.

A further object is the provision of a brassière that is self-adjusting, accommodating itself automatically to the bodily movements of the wearer, providing a perfect fit at all times and so retaining the breasts in natural shape.

A still further object is to provide a brassière that is easy to apply and/or to remove, that is worn without inconvenience, that does not hinder free bodily movement of the wearer, that does not bind, that can be worn by women with any size or type breasts and that gives the breasts a proper separation and uplift; a center inside brassière portion affording a hammock-like support at the base of each breast.

The foregoing and other objects are attained by the novel constructions and arrangements of elements hereinafter described and illustrated in the accompanying drawings, wherein:

Fig. 1 is a general perspective view of a brassière according to the instant invention.

Fig. 2 is a bassière body portion pattern employed.

Figs. 3 and 4 are enlarged sectional views taken, respectively, on the lines 3—3 and 4—4 of Fig. 1.

Fig. 5 is a view of the brassière laid flat, inside out.

Fig. 6 is a fragmentary front face view of the brassière, and

Fig. 7 is an enlarged sectional view showing a double hem feature.

The brassière body front portion 1 is formed of a single piece of cloth, the top edge having secured thereto, by a double line of stitching, the cloth strip 2; the bottom edge having secured thereto, by similar lines of stitching, a plurality of spaced strips 3, preferably five in number, the cloth at one end being formed with a hem 4 to which eyelets 5 are sewed or otherwise secured, the opposite end being formed with a hem 6 having secured thereto the piece 6a carrying metal hooks 7 for cooperation with the eyelets 5 in conventional manner.

Connecting the top and bottom strips, in spaced relation to the end hem, and sewed to the body front portion are the intermediate strips 8, 8 each formed with a branch strip 8a, an intermediate strip 8 and its branch 8a connecting adjacent bottom strips 3, the space between an intermediate strip and its branch being filled by an elastic insert 9 stitched in position, the garment portion between strips 2, 8, 3 and fabric piece 6a forming one body back portion 6b, the garment portion between strips 2, 8, 3 and hem 4 forming a second body back portion 4b. Rising from a bottom strip 3 in back portion 6b approximately midway between end hem 6 and an intermediate strip and extending almost to the top strip 2 is a dart 10. Rising from a bottom strip 3 in back portion 4b approximately midway between end hem 4 and the adjacent intermediate strip 8 and extending almost to the top strip 2 is a dart 10a; strips 8 diverging from adjacent hems 4 or 6 as they rise from bottom strips 3 in the spread out garment position shown in Fig. 5. Spaced inwardly, or toward the center of the garment, from each intermediate strip 8 are two parallel substantially arcuate double hems 11, 12 spaced approximately one-half inch apart and extending from the top strip 2 downwardly and inwardly almost to the center of the garment where they are secured to inverted Y-shaped strips 13, each strip extending upwardly from the bottom edge of the garment slightly more than one-half way to the top strip 2, the upper or stem ends of the strips diverging from each other, the lower or forked ends of said strips being substantially equidistant from adjacent branch strips 8a, each garment portion bounded by a portion of a strip 2, strips 8, 8a, a strip 3, a portion of strip 13 and a double hem 11 defining a body side portion 13a; one upon each side of the garment. Between the forks of each strip 13 are elastic inserts 15 that also occupy the space between adjacent bottom strips 3.

A body central portion 16 is bounded by double hems 12, one fork of each strip 13, a bottom strip 3 and top strip 2; the portion 16 being formed centrally and inwardly from top strip 2 to bottom strip 3 with twin tucks 17, 17, as clearly shown in Fig. 3, tapering slightly from top to bottom, lines of stitching 18, 18, Fig. 6, defining a separation portion in the body front portion upon the outer face of the garment.

Secured only to the top strip 2 and body top edge by stitching is the floating hammock-like support 19 disposed approximately centrally of the body front portion and cut on the bias from a single piece of material, this hammock support

having a transverse elastic band 20, Fig. 5, sewed thereto yieldingly providing a corset effect, the hammock support as it extends downwardly being widened as at 21 and extending laterally in both directions through three pairs of elastic loops, the first pair 22, 22 having its ends stitched as at 22a to an upper portion of strip 13 and to the juncture of the stem of that strip with its forked end, the extensions also extending through the second pair of loops 23, 23 stitched to strips 8, 8 and to double hems 11 or 12, and finally through a third pair of elastic loops 24, 24 secured to strips 8, 8 and double hems 12, 12, said hammock support extensions diminishing in width as they extend laterally and upwardly and passing over the shoulder straps 25 to the top strip 2 to which they are adjustably secured by snap fasteners 26, said shoulder straps being stitched to the garment edge and to the strip 2, said shoulder straps being provided with adjustable shoulder pads 27.

The brassière is applied by inserting the arms in the shoulder straps 25 with the hammock support next to the person, the straps 25 are moved to position upon the shoulders with the pads 27 resting directly upon the shoulders. The breasts are received in the cups or pockets upon each side of the support 19. If the breasts are large they rest upon and are supported by the relatively outer double hems 11 and smaller breasts are received in and supported by the double hems 12. The elastic inserts 9, 15, the pairs of elastic loops and the elastic band 20 permit close substantially automatic adjustment of the garment to the person when the hooks and eyes are engaged securing the portions 6b, 4b directly together at the back, the extensions 21 being adjusted to suit by means of their snap fasteners 26 which may be provided in multiple at the extension ends. The fact that the one-piece body portion is cut on the bias affords greatest elasticity and the specific hammock support embraces the breasts and gently but efficiently supports them in a natural position and there tends to stabilize them. It is not here necessary that the bottom support portion so snugly embrace the breasts as to cause dis-

comfort as the hammock support portion does approximately ninety percent of the work, the support area is a relatively large or spread out one and as a result there is no tension on the shoulders from the straps which while here not shown adjustable may obviously be made so by means of snap fasteners or the like (not shown). Many women have one bust larger than the other but the instant brassière may accommodate one in a double hem 11 and the other in double hem 12.

What is claimed is:

In a brassière, a body front portion, body back portions, body side portions connecting said body back portions to said body front portion, double hems at the juncture of said body side portions and said body front portion, shoulder straps secured to the body front and back portions, a floating hammock-like support disposed centrally of the body front portion and having a transverse elastic band secured thereto yieldingly providing a corset effect, the hammock support as it extends downwardly being widened and comprising portions diverging laterally and extending upwardly into tapered hammock support extensions through pairs of spaced elastic loops secured upon said body front portion, said hammock extensions adapted to extend over the top of the brassière pockets to which they are adjustably secured.

MARTHA A. RICHARDSON.
